BRACELET

Alfred Joseph Durante, Forest Hills, N.Y., assignor to Cartier, Inc., New York, N.Y.

Filed Apr. 24, 1974, Ser. No. 463,596

Term of patent 14 years

Int. Cl. D11—01

U.S. Cl. D11—4

FIG. 1 is a front elevational view of the bracelet showing my new design;

FIG. 2 is a left side elevational view;

FIG. 3 is a right side elevational view;

FIG. 4 is a top plan view; and

FIG. 5 is a bottom plan view.

The rear view of the bracelet is not illustrated inasmuch as same is a mirror image of the front elevational view shown in FIG. 1.

I claim:

The ornamental design for a bracelet, as shown and described.
